SELF-LOCKING VENT

Clarence E. Brown, Benton Harbor, Mich.

Application November 6, 1936, Serial No. 109,600

3 Claims. (Cl. 98—66)

This invention relates to ventilators and more particularly to roof ventilators.

The primary object of this invention resides in the provision of a leak-proof roof ventilator having a removable self-locking section or cap thereon.

Another object of this invention resides in the provision of a roof or smoke pipe ventilator consisting of an embodiment of elements secured together against leakage without the use of solder or other similar fluxing material.

A further object of this invention resides in the provision of a roof or other similar type ventilator having a particularly constructed stationary section adapted to accommodate a removable section or cap.

A still further object of this invention resides in the provision of a roof ventilator consisting of a stationary section and cap adapted to be removably assembled thereon so as to prevent rattling therebetween.

Aside from the aforesaid objects this invention resides in the provision of a roof ventilator consisting of a stationary and removable section or cap held together by locking means adapted to bindingly retain the sections against displacement and in rigid relation to one another.

With these and other objects in view this invention resides in certain novel features of construction and arrangement of elements to be herein-after more particularly described in the specification, illustrated in the accompanying drawing and pointed out in the appended claims and, while this disclosure depicts my present conception of the invention, the right is reserved to resort to such changes in arrangement and construction as come within the spirit of the invention.

In the accompanying drawing forming a part of this application:

Fig. 1 is a side view of a roof ventilator as constructed in accordance with this invention.

Fig. 2 is a plan view thereof.

Fig. 3 is an enlarged vertical sectional view of the ventilator approximately on line 3—3 of Fig. 2.

Fig. 4 is an enlarged detail side view of a portion of the stationary and removable sections showing the self-locking elements thereof.

In the present illustration of this invention the numeral 5 designates, in general, a roof or other similar type ventilator which preferably consists of a stationary section 8 and removable section or cap 8'.

The stationary section 8 consists of a suitably shaped base plate 6 having an opening 7 therein to the wall of which is connected as by flanges 11,

formed on the lower ends of outer and inner sleeves 9 and 10 respectively, said sleeves being secured together by rivets or the like and fixed to the base plate 6 by the flanges 11 so as to form a leak-proof joint without the use of solder or the like.

The outer sleeve 9 is provided with an outwardly projecting annular bead 12 adjacent its upper end, while secured to the outer surface of the sleeve, in the region of the bead and in circumferential spaced relation, are substantially resilient clamps 13 adapted to engage tangentially disposed flanges 15 formed on the lower end of a removable sleeve 14 which supports a hood 16 and skirt 17 therefrom through the instrumentality of suitable brackets 18 rigidly connected thereto as by rivets or the like. While the sleeves 9 and 10 are herein recited as an adjunct to the base plate 6 to form a roof ventilator it is within the purview of this invention to so construct the exit end of a smoke pipe for removable attachment of the cap 8' thereto.

In order to permit the clamps to readily align with the flanges 15 when assembling the removable and stationary sections, the flanges are gradually reduced in width at one of their extremities as at 15' and, upon disposing the clamps in alignment with the flanges at said reduced portions, the flanges will pass beneath the clamps upon rotating the removable section in the proper direction, thus causing the sleeve 14 to be tightened against the bead as the higher portions of the flanges slide beneath the clamps.

Although the removable section may be connected to the stationary section as heretofore stated, it is within the purview of this invention to snap the flanges 15 beneath the clamps and then establish rigidity between the sections by turning the removable section in such direction as will create a bayonet-like action between the clamps and flanges.

With this invention fully set forth it is apparent a leak-proof roof ventilator is provided without soldering the joints of the various elements thereof and, through the instrumentality of the self-locking elements, the removable section can be easily connected to the stationary section and turned until tightened.

Having thus described my invention what I claim and desire to protect by Letters Patent is:

1. In a ventilator of the character set forth the combination of, a base plate having an opening therein, inner and outer sleeves secured to the base plate in registration with the opening therein, an annular bead on the outer of said sleeves,

- peripherally spaced clamps secured to the outer sleeve in the region of the bead, a removable sleeve telescopically connected to the free end of the aforesaid sleeves, tangentially disposed flanges formed on the removable sleeve for engagement by the clamps, a hood over the removable sleeve, a skirt surrounding the upper portion of the removable sleeve in spaced relation therewith, and brackets secured to the removable sleeve and supporting the hood and skirt in spaced relation to one another.
2. In a ventilator of the character set forth the combination of, a base plate having an opening therein, a tubular section secured to the base plate in registration with the opening therein, an annular bead on the tubular section adjacent its outer end, resilient clamps secured to the tubular section with their free ends deflected outwardly and overlying the annular bead, a removable sleeve telescopically connected to the free end of the tubular section, means on the

removable sleeve engaged by the resilient clamps for seating the inner end thereof against the annular bead of the tubular section, and a hood carried by the removable sleeve in spaced relation thereto.

3. In a ventilator of the character set forth the combination of, a stationary tubular section, an annular bead formed on the stationary section adjacent its outer end, means formed on the inner end of the stationary section for securing it to a support, a removable sleeve telescopically connected to the free end of the stationary tubular section, tangentially disposed flanges formed on the removable sleeve and extending outwardly and downwardly therefrom, resilient clamps secured to the stationary tubular section with their free ends bearing on the flanges when in locked relation, and a hood secured on the removable sleeve.
